(57) **CLAIM**

The ornamental design for a plastic container, as shown and described.

DESCRIPTION

FIG. 1 is a top, front perspective view of a plastic container of the present invention;

FIG. 2 is a rear elevational view thereof;

FIG. 3 is a bottom, front and side perspective view thereof;

FIG. 4 is a top plan view thereof; and,

FIG. 5 is a bottom plan view thereof.

The broken lines in the drawings depict probable environment only, and form no part of the claimed design.
